UNITED STATES PATENT OFFICE

2,639,058

ELASTICALLY SEALED CLOSURE FOR
CONTAINERS

Frederick Lobl, Middleboro, Mass.

Application July 26, 1951, Serial No. 238,609

1 Claim. (Cl. 220—42)

1

This invention relates to improvements in closures for containers, and more particularly to improvements in such closures wherein an insert closure element is removably maintained in the mouth of a container by a sealing member which elastically engages exteriorly around the mouth walls of the container.

It is among the objects of the invention to provide a closure for containers which has a rigid plug-type of closure element which is adapted to be inserted in the mouth of a container and which has an elastic band of substantial width annularly secured to the rigid closure element in a relation to an annular outer portion of the rigid closure element such that said elastic band may be elastically engaged around the mouth walls of the container to maintain the rigid closure element in the mouth of the container, with an annular portion of the elastic band extending from its said annular securing to the rigid closure element outwardly between an annular portion of the rigid closure element and an annular adjacent surface portion of the container whereby said annular outwardly extending portion of the elastic band constitutes an annular tensioned sealing cushion drawn outwardly between adjacent annular surfaces of the container and said rigid closure element whence the major portion of the width of the elastic band extends integrally and elastically around a substantial area of the exterior surfaces of the mouth walls of the container.

Another object is to provide a container closure of the mentioned general type wherein a rigid closure element engages within the mouth of the container and an elastic band of substantial width has one edge portion secured to the rigid closure element inward of the periphery of the outer end of the rigid closure element and adapted to be drawn annularly outward between the container and an outer annular portion of the rigid closure element when said elastic band is being elastically engaged exteriorly around the mouth walls of the container.

It is, moreover, my purpose and object generally to improve the structure and effectiveness of container closures and more especially closures wherein an elastic band engages exteriorly around the mouth walls of the container.

In the accompanying drawing:

Fig. 1 is a medial cross-sectional view of the mouth end of a container and of a closure therefor embodying features of the invention, the closure being in separated relation to the container with its elastic band in its contracted inverted position;

2

Fig. 2 is a view similar to Fig. 1 but showing the closure in the mouth of the container with its elastic band in sealing relation to the mouth and elastically engaged exteriorly around the mouth walls of the container; and

Fig. 3 is a view similar to Fig. 2 but showing a modified form of container.

Referring to the drawing, the container 10 of Figs. 1 and 2 may be of any suitable material, such as glass, metal, rubber, porcelain, pottery, or any suitable one of the available plastic or composition materials, or the like. It preferably, although not necessarily, is formed with an exterior annular flange or lip 12 around its mouth opening and its mouth walls may provide a tapering neck or may have cylindrical extent as shown in the drawing.

The closure element 14 may be made of any suitably rigid material. It may be formed of plastic or composition materials, for example, although I presently prefer to make it of sheet metal with the generally shallow cup shape as represented in the drawing wherein cylindrical side walls 14a extend integrally upward from a bottom wall 14b. The cylindrical walls 14a have exterior diameter for nicely fitting the mouth of the container within the mouth walls thereof.

According to the invention a relatively wide elastic rubber band 16 is associated with the closure element 14 in such a manner that it can elastically engage exteriorly around the mouth walls of the container when the container is to be closed, with a portion drawn annularly outwardly between the end of the container and an annular outer portion of the closure element, and can be inverted into contracted enclosing relation to the outer portion of the closure element when it is desired to release the closure element for removal from the container mouth. The rubber band 16 has one annular marginal edge portion secured to an outer annular portion of the closure element closely adjacent to the exterior circumference of the cylindrical walls thereof. As represented in the drawing, the outer edge portion of the cylindrical walls 14a is rolled outwardly to provide an exterior annular bead 18, and a marginal edge portion of rubber band 16 is annularly clamped and anchored within the bead 18 with a substantial width of the elastic band free to be

stretched and drawn outwardly over the end of the container mouth walls, when the closure element 14 is within the mouth opening, thereby to engage the said outwardly stretched portion of the band between the end of the container walls and said outturned bead 18 on the closure element and to engage the major portion of the

width of the band exteriorly and elastically around the container lip 12 and adjacent portions of the mouth walls of the container. When the container is to be opened, the said exteriorly engaging portion of the rubber band 16 may be clasped by two fingers at its inner free edge portion and drawn outwardly around the bead 18, after which it will snap to its inverted contracted position of Fig. 1, leaving the closure element 14 free to be lifted out of the container mouth.

Referring to Fig. 1, it will be apparent that the closure element 14, with the rubber band 16 in its inverted contracted position, may be inserted in the mouth of the container until the rubber-wrapped bead 18 seats annularly against the end of the container 10, after which the band 16 may be stretched and urged downward by fingers inserted within the band. The band 16 obviously has substantially less diameter than the container wall portion around which the band is to be engaged, and the substantial engagement of the closure element, with nice fit in the container mouth, steadies and stabilizes the closure element within the mouth as the rubber band 16 is being stretched into snug elastic engagement around the walls of the container. Hence, the closure element is not subject to accidental displacement from the mouth or to sidewise movements during the elastic-band sealing of the container. As the free edge portion of the rubber band passes the bead 18, the elasticity of the band will tend to snap it downwardly into elastic engagement around the container mouth walls, as shown in Fig. 2, with an outward drawing and stretching of the band over the end of the container and over the container lip 12. As a result, the closing of the container mouth by the nice fit of closure element 14 therein is augmented by a double-sealing of the container by the rubber band 16. The band provides an annular cushioning seal around the circular crack between the container mouth walls and the walls 16a of the closure element 14, and the relatively wide skirting portion of the rubber band effects a broad seal around and along the container mouth walls throughout the extent of the band over and around the container lip and around the adjacent mouth walls of the container.

Obviously the anchored edge margin of rubber band 16 will be in a stretched condition when anchored, so that adjacent portions of the band constantly tend elastically to assume an unstretched condition.

Fig. 3 illustrates the closure of the invention applied to a container 10' made of sheet metal having a lip 12' in the form of an outwardly rolled annular bead over and around which and the adjacent mouth walls the elastic band 16 is elastically engaged, with the same double-sealing action as in the Figs. 1 and 2 embodiment.

It is intended that the patent shall cover by suitable expression in the appended claim, whatever features of patentable novelty exists in the invention disclosed.

I claim as my invention:

A closure for a container having walls defining a mouth opening, said closure comprising a generally cup-shaped plug formed of sheet material having a bottom wall and integral annular side walls terminating in an out-turned annular bead, an elastic band having internal diameter less than the exterior diameter of said annular side walls of the plug, said band being stretched and arranged exteriorly on said plug with one end portion of the band walls secured to the plug at said bead, the material of said bead being formed to secure said end portion of the band within the bead whereby the main portions of said band may be stretched and turned outwardly about said bead to uncover the said plug for insertion of the plug in said mouth opening of the container with portions of said band engaging between the rim of the container and said bead on the plug, said main portions of the band being then movable into resilient gripping engagement around exterior portions of the container for resiliently biasing said plug into the mouth of the container while sealing the container.

FREDERICK LOBL.
